Application September 29, 1938, Serial No. 232,286
In Germany October 12, 1937

5 Claims. (Cl. 178—7.2)

This invention relates to electron devices and more particularly to cathode ray tubes such as used in television.

The cathode ray tubes for the transmission of television pictures that are known as "iconoscopes" have a light-sensitive electrode carrying a large supply of small photo-electric particles and serving as a collecting screen for the luminous image to be transmitted. This electrode, the action of which reminds of the retina of the human eye, will be designated hereinafter as the mosaic electrode.

Each photo-electric particle constitutes one of the electrodes of a small condenser. All the condensers have in common one complementary electrode, usually in the form of a metal plate. This may be applied as a conductive coating to a solid insulating plate (the dielectric of the multiple condenser).

In consequence of the luminous radiation which they receive the photo-electric particles obtain a positive electric charge which is neutralized by the cathode ray beam that scans the image area. They must be accessible both to the luminous rays projected by the image and to the scanning cathode ray beam. In order to ensure this, the mosaic electrode is generally inclined to the undeflected cathode ray beam (inclined to the straight line which connects the source of electrons to the centre of the image area) so that the cathode ray beam or the luminous rays or both are at an acute angle of, for example, 45° with the image area. This arrangement brings about a divergence of the scanning grating from the rectangular shape, which must be obviated by particular electrical measures, or distortion of the image results, which can only be avoided with great difficulty. It would therefore be advantageous for the luminous rays and the cathode rays to be capable of being projected from opposite sides onto the mosaic electrode, the form of the tube becoming simpler and the disadvantages of the inclined projection being avoided.

In order to carry into practice this form of tube, it has previously been suggested that the photo-electric particles should be constituted by tiny rods extending from the one surface of the mosaic electrode to the other or should be arranged in the meshes of a wire gauze so as to be able to be struck on the one side by the luminous rays and on the other side by the cathode rays. The manufacture of such screens with sufficiently fine image-subdivision is extremely difficult so that any practical use of this solution has not yet been arrived at.

It has also been thought of to cause the scanning cathode ray beam to impinge on the uninterrupted common condenser electrode, it being necessary for the electrons to penetrate through the metal layer and the insulating layer for getting to the photo-sensitive particles. Thus, however, they are absorbed for the greater part so that the efficiency is still very low. In addition, interfering charges become manifest and there is the disadvantage of considerable dispersion.

According to the invention, in a mosaic electrode constituted by an insulating layer coated with a continuous metal layer on the one side and mutually insulated photoelectric particles on its other side both the insulating layer and the common condenser electrode are constituted by a transparent layer.

The invention is based on the recognition of the fact that the electrical resistance of the common condenser electrode is very high and the metal layer may thus be very thin and even thin enough for permitting the passage of light without substantial losses.

This permits of the radiation by light and cathode rays to which the mosaic electrode is subjected, being effected from opposite sides without having to tolerate the disadvantages and difficulties which in other arrangements are thus encountered. The invention enables particularly the practical manufacture of tubes in which the mosaic electrode is normal to the tube axis and to the undeflected cathode ray beam. These tubes may have their axes directed towards the object to be transmitted. The mosaic electrode may be close to the glass wall in parallel thereto so that the optical reproduction is interfered with to a less degree by defects of the glass wall.

It is also possible to constitute the mosaic electrode as a coating of the tube wall in the manner of the fluorescent screen of a Braun tube.

The advantage of the mosaic electrode device according to the invention is not limited to the arrangement thereof normally to the cathode ray direction. If the image screen is inclined in the usual manner, an optical image can be projected on it from two opposite sides and these two images may be mixed in the transmitter.

The conductive layer is preferably constituted by metals having for a given resistance a maximum transparency; platinum and rhodium are especially suitable. They are adapted to constitute extremely thin coherent layers capable of withstanding prolonged heating and contact with oxygen.

It has been found that in the novel tube, for

the modulation of the transmitter, use may be made with advantage of the stream of electrons generated by secondary emission from the photo-electric particles. This stream is obtained from an electrode arranged in the proximity of the mosaic electrode and maintained at a sufficiently positive potential, when the tube is in use. An advantage of this is that in this method less interference becomes manifest than in the use of the condenser currents flowing to the common electrode. In addition, it has been found that in some cases the currents generated by the secondary emission may be greater than the discharge currents of the elementary condensers may be. It is true that they correspond to the negative image, but the conversion of the current curve into a curve corresponding to the positive image (high current-strength with high image-brilliance and conversely) may be readily brought about by means of a discharge tube having a control grid.

In order that the invention may be clearly understood and readily carried into effect a few forms of constructions of cathode ray tubes according thereto will now be described more fully with reference to the accompanying drawing, in which they are diagrammatically illustrated.

Fig. 1 is a sectional view of a tube.

Fig. 2 shows a part of the mosaic electrode with which the tube of Fig. 1 is furnished.

Fig. 3 shows a part of a tube according to the invention in another form of construction.

Fig. 4 shows a tube in which the mosaic electrode is inclined.

The electrode system shown in Fig. 1 comprises an electron gun and serves for the production of a directional cathode ray beam. The system may be constructed in a well known manner and needs therefore no further description.

2 and 3 designate two pairs of deflecting plates for image scanning which may also be shaped in the usual form. Whereas the mosaic electrode is generally inclined to the axis governed by the electrode system, in the tube shown in Fig. 1 the mosaic electrode 4 is normal to the tube axis, which in this case has also the direction of the undeflective cathode ray beam.

The mosaic electrode comprises a metal stiffening frame 5, which has clamped in it, as shown in Fig. 2 on an enlarged scale, a transparent insulating disc 6, e. g. a mica plate. This insulating disc carries on the side remote from the electrode system 1 an uninterrupted metal layer 7. The latter may have been applied to the insulating layer by vaporization or may be made by another, e. g. a chemical method.

The mica disc 6 has on the opposite side a coating of mutually insulated photo-electric particles 8, which, as usual, may be silver with caesium oxide and caesium and are the carriers for the photo-electrically dislodged charges.

If the image-producing luminous rays are focused on to the mosaic electrode 4 by an optical system 9 they penetrate through the thin metal layer 7 and the mica layer 6 and impinge on the photo-electric particles 8 which, due to this, emit photo-electrons and assume different positive charges in proportion to the local image-brilliance. These charges are neutralized by the scanning cathode ray beam, with the result that discharge currents pulses flow in the supply conductor 10 for the condenser, it being possible for said pulses to be used in a manner known per se for modulation of a transmitter.

A suitable metal for constituting the conductive layer 7 is platinum, since it can be readily applied in the form of a uniform thin layer, which, while being thin enough not to absorb more than 10% of the incident light, is still sufficiently conductive and has no tendency of splitting up into small drops. Rhodium is even better suited than platinum since, when formed in the shape of a thin layer, it has a still greater rigidity and with identical resistance absorbs less light. The other more highly refractory metals of the platinum group are also serviceable. Since the said metals are not attacked by air it is not necessary to mount the metal layer within the discharge tube. It may be applied by vaporization in a further vacuum vessel and the metallized insulating disc may then be further manipulated in air. The photo-sensitive particles 8 may be applied in a usual manner. They may be manufactured e. g. by applying silver, by vaporization, through a sheet of gauze or by thermal disintegration of a silver layer, the silver particles being then superficially oxidized and coated with caesium.

For the purpose of applying the metal layer 7 by vaporization morsels of the metal to be vaporized may be secured to a filament of highly refractory metal, such e. g. as tungsten, and by an electric current this filament may be brought to incandescence in an exhausted space in which the insulating plate is arranged. The metal particles secured to this filament are thus caused to vaporize, the metal vapor becomes deposited on the walls of the vessel and on the insulating layer arranged in the vessel, which is thus coated with a thin metal film. It may be ascertained by optical observation or by measurement of the resistance whether the desired layer thickness is obtained. Alternatively, the metal deposit may be by an electric discharge in a gas filled space in which an incandescent filament of the metal to be worked upon is provided as a cathode.

If the mosaic electrode is to be applied to the wall of the tube, a metal deposit is first produced on the glass wall and is coated with an insulating layer. This is elucidated by Fig. 3. Since the layers are very thin the dimensional proportions as are apparent from the figure are not the true ones. The same remark applies to Fig. 2.

The end wall 11 of the tube has a metal layer 12, preferably of platinum or rhodium, formed on it by cathode disintegration, preferably in a rare gas or volatilization in the tube vessel itself.

This metal layer which is thin enough not to absorb more than 10% of the incident light has applied to it an insulating layer 13 which is also transparent. Again the latter may be made in various ways. A salt, e. g. an earth alkaline borate, may be applied to the metal layer by vaporization or a suspension of a glass of low melting temperature (so-called enamel glass) may be applied and the solvent may be vaporized. The insulating layer may be improved by melting or sintering of the insulating substance.

The layer 14 of photo-electric particles is also made by a customary method. The glass wall 11 is slightly curved for reasons of rigidity. It may also be formed by a smoothly ground and polished glass plate the edge of which has fused to it the tubular glass wall. This is less simple and requires a greater wall thickness but has the advantage of avoiding image distortion due to curvation of the image area and defects of the glass wall.

Cathode ray tubes are generally provided with a conductive coating, for example of graphite or silver, on the interior of the glass wall that surrounds the deflecting space. In a tube constructed as shown in Fig. 3 such a wall coating may be used for bringing about the electrical connection to the conductive layer 12. The conductive wall coating or a part thereof may, however, also serve for collecting the secondary electrons emitted by the particles, it being necessary to remove the excess of metal existing on the glass wall so that the metal layer 12 does not extend beyond a given limit and to maintain between the edge of this metal layer and the conductive wall coating 17 a good insulating zone, for example 1 cm. wide, designated in Fig. 3 by 15, a metal wire 16 sealed in the glass wall providing for the electrical connection to the metal layer 12. When the tube is in use, the wall coating 17 is connected through a resistance 20 to a point whose potential is constant and positive with respect to the layer 12. The said resistance has occurring in it potential differences which correspond to the secondary emission of the photo-electric particles struck by the 25 cathode ray beam and are supplied to the image transmitter via an amplifier and if desired a phase-reversing device.

It is preferable that in order to avoid interfering secondary emission from the insulating layer the photo-electric particles and the insulating layer should be separated by the braking layer, for example of aluminium which is described in U. S. Patent application Ser. No. 193,129.

A metal ring 18 is provided in the tube shown in Fig. 1 for collecting the electrons emanating from the mosaic electrode by secondary emission.

The rotation-symmetrical arrangement of the collecting electrode in a tube according to the invention assists the transmission of a uniform image by the secondary electrons. If the scanning direction is inclined it is difficult to arrange the collecting electrode in such manner that for a given image brilliance the stream of secondary electrons via this electrode is independent of the point of the mosaic electrode at which these electrons emanate.

Hitherto, the signal voltages in an iconoscope were obtained from a resistance connected to the common condenser electrode and designated in the drawing by 19. The current that flows to an electrode collecting the secondary electrons was not well adapted for this purpose, since also the photo-electrons emitted simultaneously by the photoelectric particles were absorbed for the greater part by the same electrode and produced in the resistance 20 connected to the latter a voltage which was superimposed on the signal voltage and brought about interfering effects which could be eliminated with difficulty. In the tube according to the invention this interfering phenomenon does not become manifest or becomes manifest to a considerably less extent.

Probably, this is due to the fact that for a sufficiently small thickness of the insulating layer (for example of the order of magnitude of 10μ) the photoelectrons penetrate across the insulating layer and thus they get to the common condenser-electrode from which they are conducted away by the conductor 10 or 16 respectively and the resistance 19 to the source of operating voltage. The collecting electrode 18 or 17 respectively is reached practically by the secondary electrons alone, so that the stream of electrons flow-

ing in the resistance 20 to the source of operating voltage is governed at every instant only by the secondary emission from the photoelectric particles struck at that instant by the cathode ray beam. The less positive the particles and thus the smaller the local image brilliance, the greater is the said secondary emission. If the positive image is desired at the point of reception, it is consequently necessary for the signals to be reversed at some point between the said point of reception and the image-transmitting valve in this sense that the currents to be transmitted are subtracted from a constant value. The sound technical means required for this purpose (a discharge tube having a control grid is generally used for this purpose) are well known to those skilled in the art and a further explanation in this connection may therefore be dispensed with. For the purpose of removing the interfering fields 20 the wall of the tube shown in Fig. 1 may be coated with the usual conductive layer which, if desired, may serve, instead of the ring 18, for collecting the secondary electrons.

Fig. 4 shows the arrangement hitherto used of the mosaic electrode 4 sloped with respect to the straight line which connects the electrode system 1 to the center of the screen. If in this case a transparent mosaic electrode according to the invention is used, it permits of projecting an image from two opposite sides on to the light sensitive layer and of mixing the two images electrically in the transmitter. Thus, for example, the optical system 21 permits of applying a stationary background to the image area and the second optical system 22 permits of projecting the luminous rays issuing from the movable object on to the same image area, the two images being scanned simultaneously by the movable cathode ray beam 23. It is also possible to illuminate the image area evenly from one side and to project the image to be transmitted from the other side, if it is desired for optical reasons. Irrespective of whether the luminous rays arrive from the one or from the other side, the photo-electric particles are struck by the light, which with a screen having an opaque metal plate or having small metal rods is impossible.

For the purpose of illuminating on both sides, the arrangement shown in Fig. 4 is better adapted than those shown in Figs. 1 and 3, since in these latter arrangements the side of the mosaic electrode which is adjacent the cathode can be reached by the light less readily. If desired, a mirror system of the kind previously suggested for opaque screens may be used for this purpose.

What we claim is:

1. In a television transmission system wherein a cathode ray tube is provided having within its envelope a mosaic comprising a planar transparent insulating member having a thin transparent layer on one surface and a plurality of mutually isolated photosensitive particles upon the opposite surface, the method of transmitting composite pictures composed of a plurality of images 60 which comprises projecting one image of the composite picture to be transmitted upon said photosensitive particles, projecting simultaneously from the reverse side of the mosaic another one of said plurality of images of the composite picture to be transmitted upon said transparent metallic layer, scanning said particles by a beam of electrons to release electrons in accordance with the light intensity of the elemental areas of the composite picture, and deriving point by point electric signalling impulses representative of the

elemental areas of the composite picture to be transmitted by collecting the released electrons.

2. In a television transmission system wherein is provided a cathode ray tube having within its envelope a mosaic electrode comprising a planar transparent insulating member with a transparent conducting layer on one face, and a plurality of mutually isolated photosensitive particles upon the opposite surface, said cathode ray tube being provided further with means to scan said photoelectric particles by a beam of electrons, the method of transmitting composite pictures composed of a plurality of images which comprises the steps of projecting one image of the composite picture to be transmitted upon said photosensitive particles, projecting simultaneously from the reverse side of the mosaic another of the images of said composite picture to be transmitted upon said transparent conducting layer, periodically scanning said photosensitive particles according to a predetermined pattern to eject secondary electrons therefrom, and deriving an electrical signalling current in accordance with the ejected secondary electrons.

3. A television transmission system comprising a cathode ray tube having within its envelope a mosaic formed from a planar transparent insulating member with a thin transparent metallic layer on one surface and a plurality of mutually isolated photosensitive particles upon the opposite surface, means for projecting one image of a composite picture to be transmitted upon said photosensitive particles, said composite picture being composed of a plurality of images, means for projecting simultaneously from the reverse side of the mosaic another of said plurality of images of said composite picture to be transmitted upon said transparent conducting layer, means for periodically scanning said photosensitive particles according to a predetermined pattern to eject secondary electrons therefrom, and means for deriving an electrical signalling current in accordance with the ejected secondary electrons.

4. In a television transmission system wherein a cathode ray tube is provided having within its envelope a mosaic comprising a planar transparent insulating member having a thin transparent metallic layer on one surface and a plurality of mutually isolated photosensitive particles upon the opposite surface, the method of transmitting composite pictures composed of a plurality of images which comprises projecting one image of the composite picture to be transmitted upon said photosensitive particles, projecting simultaneously from the reverse side of the mosaic another one of said plurality of images of the composite picture to be transmitted upon said transparent metallic layer, and scanning said particles by a cathode ray beam to produce output signals.

5. In a television transmission system a cathode ray tube having a mosaic electrode, comprising a transparent insulating support, a transparent metallic layer upon one surface of the support, a plurality of minute mutually isolated photosensitive particles upon a surface of the insulating support opposite to the metallic layer, means to project an image upon the mutually isolated photosensitive particles, means to project simultaneously from the reverse side of the mosaic a different image upon the transparent metallic layer, means to project a beam of electrons toward the surface bearing said particles, deflecting means intermediate said electrode and said beam projecting means to scan said particles point by point according to a predetermined pattern to release electrons in accordance with the light intensities of both projected images and impedance means connected to the mosaic electrode for deriving electrical signals representative of both of the images projected upon the electrode in accordance with the released electrons.
